GAME BOARD

Herbert M. Lewis, Westmount, Quebec, Canada, assignor to Derbie Line Limited, Montreal, Quebec, Canada

Filed Aug. 15, 1960. Ser. No. 61,749

Term of patent 14 years

(Cl. D34—5)

The figure is a plan view of a game board, showing my new design. The game board has no appreciable thickness.

I claim:

The ornamental design for a game board, as shown and described.
